CLAIM

The ornamental design for a combination mouthwash and cup dispenser, as shown and described.

DESCRIPTION

FIG. 1 is a front elevational view of the combination mouthwash and cup dispenser showing my new design; FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken-line disclosure of a portion of a cup and indicia in FIGS. 1 are 7 and for illustrative purposes only and form no part of the claimed design.

FIG. 1

FIG. 2

*FIG. 3**FIG. 4**FIG. 5**FIG. 6*FIG. 7
